UNITED STATES PATENT OFFICE.

GEORGE KONSTANTINIDES, OF EAST PITTSBURG, PENNSYLVANIA.

STOOL.

965,113.

Specification of Letters Patent.

Patented July 19, 1910.

Application filed June 11, 1910. Serial No. 566,423.

To all whom it may concern:

Be it known that I, GEORGE KONSTANTINIDES, a subject of the King of Greece, residing at East Pittsburgh, in the county of Allegheny and State of Pennsylvania, have invented certain new and useful Improvements in Stools, of which the following is a specification, reference being had therein to the accompanying drawing.

10 This invention relates to stools and has for its object to provide a stool which is particularly adapted for use in connection with the counters for soda-fountains, department stores, lunch counters and for any 15 other purposes wherein it is found applicable, and the primary object thereof is to provide a stool in a manner as hereinafter set forth which can be conveniently raised or lowered to increase or decrease the height 20 of the stool and when so adjusted secured in position.

A further object of the invention is to provide a stool in a manner as hereinafter set forth which can be made a fixture upon 25 the floor of a store or provided with feet for firmly supporting the same so as to permit of the stool being moved from point to point when desired.

Further objects of the invention are to 30 provide a stool which is comparatively simple in its construction and arrangement, provided with an adjustable foot rest, conveniently adjusted, strong, durable, efficient in its use, and comparatively inexpensive to 35 manufacture.

With the foregoing and other objects in view, the invention consists of the novel construction, combination and arrangement of parts as hereinafter more specifically described and illustrated in the accompanying drawings wherein is shown the preferred embodiment of the invention, but it is to be understood that changes, variations and modifications can be resorted to which come 45 within the scope of the claims hereunto appended.

In the drawings wherein like reference characters denote corresponding parts throughout the several views: Figure 1 is a 50 front elevation of a stool constructed in accordance with this invention. Fig. 2 is a vertical sectional view thereof, and, Fig. 3 is a plan of a detached foot ring.

Referring to the drawings in detail, 1 55 notes a circular base having a centrally dis-

posed tubular pedestal 2 communicating with a vertical opening 3 formed in said base, and this opening communicates with an annular recess 4 in the bottom of the base. The base 1 is provided with a peripheral flange 5 having a plurality of spaced vertical openings 6 whereby the base can be secured to a floor by screws, nails or similar fastening means. The openings 6 of the flange 5 also permit of the base being 60 connected to a foot ring 7 having radially disposed feet 8, said ring being connected to the base when it is desired to move the stool about.

9 designates a tubular standard telescoping the pedestal 2. This standard adjacent to the lower end thereof is provided with peripheral ribs 10 forming a guideway for a two-part band 11 having oppositely-disposed foot rests 12 and 13. The parts of the 75 band 11 are connected together by screws 14 and to fix the band relative to the standard 9. The foot rest 13 is provided with an opening 15 and locked in said opening is a set screw 16 having a bearing head 17 for 80 frictionally engaging the standard 9 and holding the band in an adjusted position.

18 designates a plurality of circumferentially arranged grooves formed in the inner side of the standard 9, each of said grooves 85 having the lower wall beveled as at 19. Adapted to engage in said grooves are the beveled teeth 20 of locking arms 21 and 21^a, located in the pedestal 2, the latter being provided with diametrically opposed openings 22 for the teeth 20. The arms extend 90 downwardly through the opening 3 of the base 1 and are provided with right angular extensions 23 within the recess 4. The extensions 23 are pivotally connected as at 24, 95 to depending lugs 25 carried by the base 1 within the recess 4. The outer ends of the extensions 23 are provided with sockets 26 for the lower ends of coil springs 27 housed within the base 1. The extension 23 of the 100 arm 21^a has attached thereto the angular end 28^a of a lever 28 which is pivoted intermediate its ends upon a pin 28^b arranged within the recess 4 in the bottom of the base 1. The lever 28 is pivotally connected as at 28^c 105 to the lower end of a link 28^d which is loosely connected as at 29 to the locking arm 21. The link and lever connection between the arms 21 and 21^a is provided to cause the simultaneous shifting of the arms 110

21 and 21^a from locking position when the arm 21 is shifted. The shifting of the arm 21 will be hereinafter referred to.

30 designates a set screw mounted in the standard 9 and which extends into a vertically disposed groove 31 provided therefor in the pedestal 2, said set screw when extending into said groove preventing the standard 9 from rotating relative to the pedestal 2.

32 designates an angularly disposed opening formed in the base 1 which communicates with the opening 3 thereof. In the opening 32 is detachably mounted a plug 33 for a rod 34, said rod having the inner end thereof provided with a tooth 35 for engaging in a notch 36 formed in the arm 21. The outer end of the rod 34 is provided with a button or treadle 37, and encircling said rod between the plug 33 and the tooth 35 thereof is a coil spring 38 adapted to normally hold the tooth of said rod out of engagement with the arm 21.

39 designates a cylindrical socket carried by the upper end of the standard 9, and movably mounted in said socket is a depending post 40 of a seat frame 41. The lower end of the post 40 is provided with a recess 42 to receive a coil spring 43 mounted in the socket 39 for normally supporting the seat frame 41 in an elevated position. To limit the movement of the post 40 within the socket 39, said socket is provided with detachable plugs 44 for set screws 45 which extend into an annular groove 46 formed in the periphery of the post 40. To lubricate the post 40 and insure a non-frictional movement of said post relative to the socket 39, the latter is provided with packing grooves 47 for a conventional form of packing (not shown). The lower end of the standard 9 is provided with a similar groove 48.

49 designates a circular seat secured to the frame 41, said seat having a central recess 50 for a transparent plate 51. In the recess 50 can be placed a piece of paper or plate 52 containing directions for operating or manipulating the stool, these directions being observed through the transparent plate 51.

53 designates a seat rim connected to the seat 49, as at 54, said rim being provided with a circumferentially arranged groove 55 and that portion of the ring forming the back of said groove is serrated or roughened, whereby matches inserted in the groove can be easily struck, it being practically impossible to strike matches upon the curved outer surface of the seat rim, the groove will be naturally selected for such purposes, thus preventing the seat rim from being marred or injured by matches.

The tension of the spring 43 is sufficient to normally support the lower end of the post 40 above the bottom of the socket 39

when the seat is occupied, also permitting of the seat being partially revolved either to the right or the left.

The foot rests 12 and 13 are positioned whereby a person to conveniently use the same must sit upon the stool, either facing a counter or with their back turned to the counter.

It will be observed that by gripping the seat rim 53, the standard 9 can be easily elevated upon the pedestal 2 and held in an elevated position by the teeth 20 which are maintained in engagement by the arms 21, 21^a which abut against the inner face of the pedestal 2 and are maintained in abutting engagement by the springs 27 which engage the angular ends 23 of the arms 21, 21^a. The arms 21, 21^a are released by pushing inwardly the button or treadle 37. This operation shifts the arm 21 upon its pivot 24 and at the same time forces the link 28^a outwardly so as to shift the lever 28 upon its pivot 28^b which causes the angular end 23 of the arm 21^a to rock on its pivot and shift the arm 21^a inwardly. When the arm 21 is shifted inwardly by the treadle or button 37 and the arm 21^a inwardly, due to the action of the link 28^a and lever 28, the teeth 20 are moved from engagement in the grooves 18 and the standard 9 can then be lowered. When pressure is relieved upon the button or treadle 37 the arms 21 and 21^a are restored to locking position due to the action of the springs 27.

100

What I claim is:

1. A stool comprising a base, a tubular pedestal carried thereby and provided with a pair of openings, a shiftable standard mounted upon said pedestal and having its inner face provided with a series of annular grooves arranged one above the other and each having its lower wall beveled, a pair of spring-pressed and oppositely-disposed arms arranged within the pedestal and base and each having a laterally-extending tooth adapted to project through an opening and engaging in a groove to arrest the downward movement of the standard, a seat supported by the standard, a link and lever connection between said arms whereby the arms can be simultaneously shifted to move the teeth out of the grooves to release the standard, and means for shifting one arm whereby both of the arms will be shifted.

105

2. A stool comprising a base, a tubular pedestal carried thereby and provided with a pair of openings, a shiftable standard mounted upon the pedestal and having its inner face provided with a plurality of angular grooves one arranged above the other, a seat supported by the standard, a pair of spring-pressed and oppositely-disposed arms arranged within the pedestal and each having a laterally-extending tooth adapted to project through an opening and engage in a

110

115

120

125

130

groove to arrest the downward movement of the standard, a pivoted lever having an angular end connected to one of said arms, a link loosely connected at one end to the 5 other of said arms and to said lever, said link and lever mechanism providing means whereby one arm will be shifted to released position with the other when the latter is

shifted to released position, and means for shifting one of the arms to released position. 10

In testimony whereof I affix my signature in the presence of two witnesses.

GEORGE KONSTANTINIDES.
